(57) **CLAIM**

The ornamental design for a television receiver, as shown and described.

DESCRIPTION

1. Television receiver

1.1 is a front perspective view of a television receiver showing our new design;

1.2 is the front view thereof;

1.3 is the back view thereof;

1.4 is the left side view thereof;

1.5 is the right side view thereof;

1.6 is the top view thereof;

1.7 is the bottom view thereof;

1.8 is an enlarged view of a portion of the television receiver shown in 1.1;

(Continued)

1.9 is an enlarged view of a portion of the television receiver shown in **1.4**;

1.10 is another front perspective view showing the television receiver in an environment of use; and

1.11 is another front perspective view shown in an alternate position.

The dash-dot broken line portions of **1.1**, **1.4**, **1.8** and **1.9** are included to show partially enlarged views only and form no part of the claimed design.

The broken lines shown in **1.10** are included for the purpose of illustrating environment and form no part of the claimed design.

The broken lines shown in **1.11** depict portions of the television receiver that form no part of the claimed design.
